(57) **CLAIM**

The ornamental design for a case for electronic device, as shown and described.

DESCRIPTION

FIG. 1 is a front perspective view of a case for electronic device, comprised of an inner shell and outer frame, showing my new design in an assembled state;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded front perspective view thereof, showing an inner shell and an outer frame of the case for electronic device separated for clarity of disclosure;

FIG. 10 is an exploded rear perspective view thereof;

FIG. 11 is a front perspective view showing only the inner shell for clarity of disclosure;

FIG. 12 is a rear perspective view thereof;

FIG. 13 is a front perspective view showing only the outer frame for clarity of disclosure; and,

FIG. 14 is a rear perspective view thereof.

The broken line showing of environment is for illustrative purposes only and forms no part of the claimed design.
